UNITED STATES PATENT OFFICE.

THOMAS JAMES BERRYMAN, OF ARMAGH, IRELAND.

ELECTRIC TELEGRAPH RECEIVER.

Application filed October 28, 1925, Serial No. 65,308, and in Great Britain November 17, 1925.

This invention relates to electric telegraph receivers and refers to the class which are provided with means for translating the required message, or desired action at the 5 receiving station, the message or action desired at the receiving station being selected by the sender at the transmitting station whereby messages, or communications, or operations, mechanical or otherwise, can be 10 controlled or selected at the transmitting station and translated or carried into effect at the receiving station, the required action at the receiving station being completed through mechanical means, or through magnetic 15 means, or through the completing and (or) breaking of electric contacts to effect the operation and (or) to arrest the operation of other mechanism.

According to this invention the translating means at the receiving station is such that it is possible, without confusion, to receive opposite signals, and signals of the same time value, in different order. When employing Morse for transmission of roman 25 letters, the signals for the letter "A" are the opposite of the signals for the letter "N" both having the same time value; again, the signals for "B" are the opposite of the signals for "V"; and, also, other signals in 30 the Morse code are represented by opposites, so that, to avoid confusion and to obtain the desired selection or storage and translation at the receiving station, the means provided at the receiving station is adapted to 35 have movement given to it in the desired directions, with signal controlled escapement means or guides, channels, pins or equivalent whereby opposite signals are differentiated; for example, an oscillatory or 40 a rotary or turning movement round a centre and an axial movement, the combination of the said movements being employed to translate the received signals into the desired characters, for example roman letters, 45 or to translate the signals received into the operation of mechanism according to predetermined combinations of signals. Control of movement of the translating device, or devices, in the desired directions, and, if desired, of printing or recording means, may 50 be effected by magnetic, motor driven, suitably timed continuous or intermittent movement in the desired direction or directions, or suitably controlled escapements or escapement actions. I may, for example, pro-

vide a suitable type carrier, or striking arm, or its equivalent, and impart to it the required movement by providing one or more electro-magnetic, pawl and ratchet or ratchet rack arrangements, giving the required 60 directional movements, working in conjunction with guides, channels, or pins, or their equivalent, or I may provide motor driven escapements operated by electro-magnets, or a combination of such means, so constructed and arranged as to provide for storage translation and printing or recording of incoming messages in the desired characters, said means being also, preferably used to cut out, or start, the recording 65 mechanism. The storage and translating mechanism may be adapted as control means to effect the control of other mechanism either mechanically or by magnetic means, or through the completing and (or) breaking 70 of electric circuits.

Incoming signals may operate clutch mechanism or gearing to produce timed sliding and (or) turning motion, when required, from a suitable source of power.

Where it is intended to receive and print messages transmitted in Morse code I may provide two motor driven escapements controlling the movement, in the desired directions, of a detachable type drum (detachable 85 for change of characters if desired and which might be used for de-coding purposes) with a relay, or equivalent to operate a dot signal escapement or movement of the printing drum in one direction and an electromagnet, or equivalent, to operate the dash signal escapement, or movement of the printing drum in another direction. When a dot signal is received it operates the relay or equivalent and allows the dot signal escapement to impart movement, in the required direction, to the type drum. If the dot signal is prolonged until it becomes a dash signal, the electromagnet is also operated and allows the second escapement to impart a 90 second and different movement to the type drum. The effect of this double movement of the type drum is such that when, say the letter "B" is received in Morse signals, the letters E, T, N, D and B pass, in turn, the 95 printing position and printing only takes place when the relay remains in spacing position long enough to allow another, and slower, printing magnet or equivalent to bring printing mechanism into action by the 100 105 110

- energizing of the magnet. The action of the printing magnet or equivalent may be used to move stops or pallets out of the escapement wheel teeth of both escapements, 5 allowing forward movement until the desired stops are reached. The type drum is then in zero or starting position and the instrument is ready for the reception of the signals corresponding to the next letter.
- 10 The following may be given as examples of the operation of switches as described. A pin, or other projection, working in conjunction with the type drum, if desired, or working independently, if desired, would be 15 so moved as to act as a wiper contact, or so as to operate a push button contact switch, or switches, or to energize a slow acting electro-magnet switch, or equivalent, adjusted so as to act only at predetermined positions of the pin or other projection. Alternatively, I may provide a suitable shaft 20 acting in conjunction with the type drum if desired, or acting independently if desired, the shaft being given movements in accordance with the invention, and carrying a member, for the making and breaking of electric circuits, when, at the required time, an electromagnet, or equivalent, presses the member against the required contact or 25 push pin, or equivalent, for the completing of the required electric circuit whereby any desired mechanism may be controlled as described. Means as described may be used 30 to make contacts to produce, through relays, or other driving means, selective movement of signal translating and printing mechanism in lieu of, or in addition to, the means hereinbefore described for this purpose.
- 35 The invention will now be described with reference to the accompanying drawings whereon examples are given of how the invention may be carried into effect.
- 40 Fig. 1 is a diagrammatic illustration, in plan view, of a form of the invention adapted for one escapement and to receive Morse signals and translate same into roman letters, the printed message being obtained in roman letters, the message received by the apparatus being in Morse code. The apparatus shown is also adapted for the operation of switches, etc. if required.
- 45 Fig. 1^a is a diagrammatic view, in elevation, of an escapement mechanism which could be used both as escapement and pin control hereinafter described with reference to Fig. 1 and also of the escapement mechanisms 4 and 11 hereinafter described as employed in connection with the apparatus 50 described with reference to Fig. 3. Other forms of escapements, or escapement stops, may be used as desired and the form shown is only used for illustration because it serves for use at all positions.
- 55 Fig. 2 is a diagrammatic illustration of

means which may be employed for energizing the dot operated magnet twice during the receiving of a "dash" signal.

Fig. 3 is a diagrammatic illustration of a modified form of the invention.

Fig. 3^a illustrates the developed plan of the translating cylinder shown in Fig. 3.

Fig. 3^b illustrates the developed plan of the printing cylinder shown in Fig. 3.

Fig. 4 illustrates to an enlarged scale the developed plan of a cylinder having guide channels, or equivalent, capable of receiving dot and dash signals and translating the same into movements of the cylinder 3^a (Fig. 4^a) to bring the roman letters or numerals thereon into printing position and holding same there long enough for the printing action to take place. For the sake of simplicity, only the letters of the roman alphabet and numerals are shown in the examples given but it will be understood that all the usual punctuation marks, signs, etc. would be provided for in a similar manner and other additional signals provided for if necessary.

Fig. 4^b shows on a similar enlarged scale a modification of Fig. 4 in which the channels are replaced by projections on the surface of the cylinder, the dot and dash pins in this case being replaced by members sliding on the profile projections on the cylinder.

Fig. 5 shows to an enlarged scale another modification in which a single pin working in conjunction with channels and projections produces the required translatory movements of the type carrying drum. Spring and (or) other means would be provided to keep the projections in contact with the pin during translating action, and also to effect the return to zero position.

Fig. 6 is an illustration also to an enlarged scale of another modification of the translating cylinder, projecting pins being used in place of the channels, or projections shown in the previous figures.

Fig. 7 shows a form of return guides for the selective cylinders illustrated at Figs. 4 to 6.

Fig. 8 is a diagrammatic representation of the operation of switches, by means of the invention either for the purpose of effecting the operating of other mechanism or for storage purposes.

Fig. 9 is an alternative arrangement to Fig. 8 and for the same purpose or purposes.

Referring to the drawings:

In the example shown at Fig. 1, the main shaft 1 carries a drum 2 and a drum 3, the drums 2 and 3 being connected together so that they move simultaneously and any rotary or oscillating movement given to the drum 2 will produce an oscillating or corresponding movement of the drum 3 and, similarly, any axial movement given to the drum

2 will also be given to the drum 3. Any axial movement of the shaft 1 produces a corresponding axial movement of the drums 2 and 3. At the end 1^a of the shaft 1 I 5 provide an escapement 4 (see also the detail in elevation Fig. 1^a) operated by an electro-magnet 5 and adapted to effect an axial stepping movement to the main shaft 1 by means of a crank 6 and connecting rod 7 10 which is connected with the end of the shaft 1 by a universal joint connection 7^a the sleeve 8 having means to prevent its turning for example a pin 8^a projecting therefrom and working in a suitable slide 8^b. The 15 spacing of the teeth on the escapement wheel 4^b is such as to produce the required number of steps (axially) of the shaft 1. Parallel with the main shaft 1 is a secondary shaft 9 which has mounted at its end 9^a 20 an arm 10 carrying a lever 10^a to cause the withdrawal of one of the pins 4 of escapements. The pins or stops 4^a are operated by the electromagnet 5 and control through the escapement 4, axial movement of the 25 main shaft 1. On the shaft 9 there is also secured an arm 10 carrying a lever to cause the withdrawal of the controlling pin 12^a. The pins 12^a and 12^b are controlled and operated by an electromagnet (not shown) 30 and adapted to produce turning movements of the drums 2 and 3. The members 10 and 10^a are mounted on the same shaft 9 so that when required, as, for example, when printing has taken place means may be provided for lifting one of the pins or stops 4^a 35 and one of the control pins 12^a or 12^b clear in order to allow of a quick return action of the translating drum 2 and the type drum 3 to the zero or starting position. 40 In the example shown in Fig. 3 there is also a secondary shaft 9 having the pin action control members thereon. In this case also the action of the printing magnet or equivalent is used to move stops or pallets out 45 of the path of the escapement wheel teeth of both escapements allowing forward movement until the desired stops 40 and 41 are reached. The type drum is then in the zero or starting 50 position and the instrument ready for the reception of the signals corresponding to the next letter. One of the stops namely 40 in this action applies to both the example given at Fig. 1 and the example given at Fig. 3. 55 Figs. 4 and 6 illustrate diagrammatically the developed plan views of different forms of translating cylinders for controlling the type drum 3 and adapted for use in apparatus such as shown at Fig. 1. The type drum 60 3 in all cases shown has its letters and numerals in the same relationship for the sake of simplicity in description but it is to be understood that these are only examples and that the signals received may vary with the 65 requirements, also that the translating sig-

nals, whether produced in the form of printed messages, or translated into operation of mechanism, may be modified to suit different requirements without departing from the invention. The form of translating cylinder used in the diagram Fig. 1 may 70 be any of the forms illustrated or any other form. The translating and printing means are not necessarily of cylindrical form, they may be flat spherical or of disc form and 75 their movements arranged accordingly. When pins are used as in diagram Fig. 6, a star wheel and jumper, or equivalent device of known construction will require to be added in order to ensure step by step turning movements of the drum and maintain the row of type selected in line with the striking hammer of the printing mechanism. This jumper could be pivoted on an arm 80 mounted on the shaft 9, and it would require 85 to be moved clear just as the pins or stops 4^a and one of the pins 12^a and 12^b has to be moved clear (the other being clear) in order to allow quick return of the drums 90 to zero position.

Each time the electromagnet 5, Figs. 1 and 2 (hereinafter referred to as the dot magnet) is operated it causes a forward axial movement of the drum 2 in the direction of the arrow 2^a and when used with 95 selective means on the drum such as illustrated at Figs. 4 to 6 or equivalent and with electromagnetic stepping action, or with one escapement stepping action, the dot magnet 5 requires to be operated to cause two steps 100 during a dash and once for a dot when translating Morse signals into roman letters and numerals. This provision is designed to simplify the selective action and 105 prevent too many letters coming abreast on the type drum 3.

Where two escapements are used as shown at Fig. 3 it is not necessary that the dot magnet 5 should be used twice for a dash as the same effect is obtained by allowing 110 the type drum 3, or its equivalent, to turn through different angles.

The mechanism shown at Fig. 2 illustrates diagrammatically how the dot magnet 5 may be energized twice through the 115 reception of a dash signal.

The action of the apparatus shown diagrammatically at Fig. 2 is as follows:—

When a dash signal is received the dot magnet 5 is operated and at the end of the 120 stroke of its armature 5^a an extension 5^b of the latter moves a member 14 causing the latter to complete the contact 15 so that electricity can flow through the contact 15 to the magnet 13 whereby its armature 13^b is 125 moved and a spring extension 13^c is brought into action to hold the contact 15 closed until the incoming current is broken or reversed. Towards the end of the stroke of the armature 13^b of the magnet 13 (the con- 130

tact 15 being held closed in order not to release the magnet 13) contact is broken at 16 by means of a catch 13^a and through the breaking of the contact at 16 in this manner the magnet 5 is deenergized or released. At the end of the return stroke of the armature 5^a of the magnet 5 the catch 13^a is so moved by action between members 5^e and 13^f that the catch 13^a permits of the re-making of the contact at 16 and thereby allowing of the operation of the magnet 5 a second time. When in spacing position the contact at 17 is closed whereby the printing magnet (not shown) is brought into action at the desired time.

Mechanical or electrical stepping arrangements may be used, other than that shown at Fig. 1, for effecting the stepping movement of the translating means suitable release and spring return means would be provided. If desired, the two steps may be obtained by adding an additional stepping magnet thereby dispensing with the releasing mechanism shown at Fig. 2. In this case the magnet 13, in addition to moving selective mechanism as described, also acts as a relay to operate the additional stepping magnet.

If desired the magnet 13 may be used as a stepping magnet and when so used an arm attached to or operated by the armature 13^b of the magnet 13 would be used to strike pins, or otherwise operate dash selective mechanism whilst the magnet 5 operates dot selective mechanism or magnet 5 towards the end of its armature stroke and insert the pin in guide channels of Fig. 5. When two stepping magnets are used and provided with overthrow stops means would be provided to lift or remove the overthrow stop of the magnet 5 so as not to prevent the second stepping magnet from acting.

The speed at which this instrument will receive ordinary or time Morse depends on the time occupied or the interval of time between the first or dot step and the second step (dash), also the time occupied to bring in printing action.

The instrument ought to be adjusted so that the second step will occur if signal is prolonged approximately twice dot length. The printing magnet ought also to act at approximately twice dot duration in order to give the requisite time for the selective apparatus to return to zero. Suitable means should be employed (electrical and (or) mechanical) to occupy the required time in bringing in or causing the second step and printing action.

In ordinary Morse, the dash is translated by means of two steps or movements. This occurs in both forms shown. If desired the dot could be translated by two or more steps and the number of steps for a dash signal modified accordingly. In single needle

Morse or plus and minus Morse of uniform time duration a single step for each signal would suffice, and the translating means would be modified to suit such requirements. Modifications could be adopted to suit other 70 codes.

All the instruments in a circuit may be adapted each to receive its call signal whilst working at a slow speed and when the call signal is translated and received it will 75 change the called instrument to work at high speed to receive the signalled message and when finished may revert automatically or otherwise to slow speed again. Means may be used to prevent the dot magnet acting or 80 responding unless a marking signal is received which is slower or of longer duration than the high speed dash signal. This is to prevent the instrument operating except when the longer or slower call signals are 85 received.

This avoids wear and tear of each instrument not required whilst other instruments are working at high speed. Speed reducing action may be obtained by mechanical or 90 electromagnetic means. Space between words may be readily obtained by the closing or breaking of contacts by the printing mechanism at the end of the printing action. The printing striker, or hammer may be of any 95 suitable form and is not shown for the sake of simplicity. It is essential that the printing striker or hammer should work with a piano-like action so as not to hold the type 100 drum 3 in any way or prevent its return to zero when freed by the other mechanism as hereinbefore described. Diverting pins which are lifted out of guide channels, or equivalent, by printing action, or by the action of the printing magnet, would be held 105 clear of the guide channels, or equivalent by means of a pivoted catch whilst a pin or equivalent carried by the main shaft 1 or placed in a suitable position would be used to strike the catch out of the way when the 110 zero position is reached allowing the dot selective pin to re-enter the dot channel or otherwise act on the dot selective arrangement. Where one or two escapements are 115 used and the selective guide channels, or pins, a cam may be provided to remove the pivoted catch and ensure the return of the secondary shaft 9 to the zero position.

Where projecting guides, guide channels, or pins, such as illustrated at Figs. 4 to 6 are used for the selective action, return guides 19 and 20 may, as shown, at Fig. 7, be provided in connection with the selective or translating drum 2. These guides follow the extreme diverting movement and they come together to form a narrow opening or channel at the zero position. Suitable pivoted levers or stops 21 and 22 would preferably be used to prevent overthrow. A pin fixed on the main shaft 1 125

- coming into contact with the guide 19 or 20 must return to the exact zero position following any diverting movement given to the translating drum 2.
- 5 The magnet 5, Fig. 1, in addition to its action as described with reference to Fig. 2 also moves the escapement 4 or its equivalent electromagnetic stepping action to produce the step by step axial movement of the main 10 shaft 1 as hereinbefore described. The magnet 13 in addition to its operation described with reference to Fig. 2 operates the cylinder turning mechanism. In this case the cylinder turning mechanism comprises 15 the controlling or diverting pins 12^a and 12^b as that when a dash signal is received the electromagnet, acting on a rocking arm and in conjunction with suitable spring means, causes the dot diverting pins 12^a to be lifted 20 clear of the projections on the drum 2 and bringing the dash diverting pin 12^b into action to turn the drums 2 and 3 in the required direction. The dash diverting pin 12^b may be lifted out of engagement with 25 the projections on the drum 2 and the dot diverting pin, acting on the drum 2 turns same in the desired direction. These movements of the pins 12^a and 12^b are obtained by the operation of the magnet 13. Similarly, when translating channels are used 30 in a drum, or projections or pins as shown in the examples of developed drums at Figs. 4 to 6 mechanism such as described and shown with reference to Fig. 1^a can be used to insert the dash diverting pin in the dash channels, at the same time lifting the dot diverting pin out of the dot channel and vice versa. It will be understood that it is not necessary that the diverting action 35 should take place every element or signal received. The dash magnet, may, for example, be energized but not operated when a series of dots are being recorded.
- If desired the dot selective pins and the dash selective pins (Fig. 6) could be arranged in three distinct groups (as shown) placed at different parts of the main shaft. The channels, or equivalent, could be separated in like manner but in two groups.
- 50 The essential elements and the manner of operating the apparatus hereinbefore described with reference to Fig. 3 and given as an example of carrying the invention into effect, might be very briefly stated as follows:—
- There is a drum 3 carrying, say roman letters, and adapted for either rotational movement or axial movement. One escapement 4, or equivalent means of imparting 55 intermittent motion to the drum 2 (which has teeth thereon of different lengths axially to allow selective action by permitting the drum 2 to turn through different angles past the stops 4^a and thus give a corresponding rotational movement to the drum 3) be-
- ing adapted to move the drum 3 rotationally on receipt of a dot, while a second escapement 11 is adapted to give axial movement to the drum 3 on receipt of a dash after the first escapement is acted. Thus, 70 in the example mentioned, in the preamble, say the letter B, indicated in Morse by a dash and three dots, the action is as follows:—
- When the key of the transmitting instrument is put down it causes the dot escapement 4 to rotate the drum 3 and bring on the letter E (a single dot). On the key being still held down the dash escapement 11 acts and gives an axial movement to the 75 drum 3 and thus brings on the letter T (a single dash). When the key is again put down, the dot escapement produces further rotation of the drum 3 and brings on the letter N (a dash and a dot). Similarly two 80 further depressions of the key produce two further rotational movements of the drum 3 bringing on, in turn, the letter D and finally, the letter B. Thereafter there is a slight pause, long enough to allow a magnet 90 (not shown) to actuate a striking arm causing printing and, simultaneously, the drum 3 is returned to its initial position, ready for the next letter.
- As an example of operating switches or the electrical operation of mechanism through the medium of switches, I have added a simple illustration of how this might be carried out. For simplicity I have added 95 it on the end of the shaft 1 Fig. 1. The shaft 1 has already been described as being given turning and axial movements, such movements being obtained by selective apparatus from signals received by it. At the 100 end 1^b of the shaft 1 a pinion 23 is mounted and so supported that it can rotate or turn with the shaft 1 when the latter is turned. Connected with a sleeve 24 on the end of 105 the shaft 1 is a contact finger or lever 25 and a rack 26. The contact finger 25 is moved over a switch-board 27 carrying a number of contacts 27^a. The rack 26 is engaged by the toothed wheel 23. As the main shaft 1 is moved axially, step by step, or otherwise, the contact member or lever 110 25 is also moved with it and as the main shaft 1 rotates, or is turned, the pinion 23 correspondingly moves the contact finger 25 laterally to the right or to the left of the 115 centre line so that contacts 27^a thereon are selected by the contact member 25 as required and when the contact member 25 is in contact with a particular contact 27^a the desired operation of mechanism or the like 120 will be effected.
- Pins or contact members carried by the main shaft 1, and moving therewith, may serve the same purpose as the contact member 25 and may act on contacts arranged 125 round the shaft 1 or on the inner surface 130

of a cylinder or in any suitable manner effect the desired action, electrical or mechanical or any combination thereof to fulfil the purposes of the signal received by 5 the apparatus and translated by it into the desired record or action or both record and action if desired.

In the example shown at Fig. 8, the end 25^a is shown as a leaf spring with a contact 10 at its ends 25^b and below same a movable member or table 28 controlled by an electromagnet 29 which may be operated in the same manner as the striking hammer of the printing mechanism or otherwise as may be 15 desired. When the electromagnet 29 is operated it raises the table 28 and the contact 25^b causing the latter to lift a sliding member 30 through a fixed table 31 in order to cause the contact member 30 to close spring 20 contact switch 32. When the member 30 is raised as described a spring catch 33 engages a notch 34 and so maintains the switch 32 closed until the spring catch 33 is moved sidewardly by suitable means whereupon the 25 member 30 will be released and will return to its original position breaking the contact 32.

The example shown at Fig. 9 operates in a similar manner to the example shown in 30 Fig. 8, the only difference being that the rod 35 takes the place of the table 28. In this case the lever arm 25^a is connected with the rod 35 at 35^a by a ball and socket or equivalent connection. The rod 35 is connected 35 by a ball and socket or equivalent connection with a lever 35^c operated by the armature 29^a of the magnet 29. In this arrangement the contacts 32 are arranged in the form of a portion of a sphere. Both of the 40 arrangements shown at Figs. 8 and 9 can be used for the storage of letters or signals for any desired purpose. The releasing action of the sliding catch 33 may be effected automatically on the receiving of a particular 45 letter signal by a selective apparatus.

Having now fully described my invention what I claim and desire to secure by Letters Patent is:—

1. In electric signalling apparatus, means 50 for directly and mechanically translating Morse code signals comprising a translating device mounted for both axial and rotary movement, means operated by every impulse adapted to act on the translating device to 55 produce one kind of movement thereof, means operated by impulses of one kind only adapted to act upon the translating device to produce the other kind of movement thereof, and means for returning said translating device to its initial position at the end of each signal.

2. In electric signalling apparatus, means 60 for directly and mechanically translating Morse code signals comprising a translating device having a series of guides thereon,

means operated by signal impulses adapted positively to move the translating device, two pins located close together and co-operating with the guides on the translating device to actuate this selectively and means 70 operated by the signal impulses for actuating said pins.

3. In electric signalling apparatus, means for directly and mechanically translating Morse code signals comprising a translating 75 device mounted for both axial and rotary movement, a signal operated device adapted positively to impart axial movement to said translating device, and a signal operated device adapted selectively to determine the 80 amount of rotary motion of the translating device.

4. In electric signalling apparatus, means for directly and mechanically translating Morse code signals comprising a translating 85 device mounted for both axial and rotary movement and having guide members thereon, a signal operated device adapted positively to impart axial movement to said translating device, and signal operated 90 means co-operating with said guide members adapted selectively to determine the amount of rotary motion of the translating device.

5. In electric signalling apparatus, means 95 for directly and mechanically translating Morse code signals comprising a translating device mounted for both axial and rotary movement and having guide members thereon, a signal operated device adapted 100 positively to impart axial movement to said translating device, a pair of adjacently disposed pins co-operating with said guide members adapted selectively to determine the amount of rotary motion of the translating 105 device and signal operated means for actuating said pins.

6. In electric signalling apparatus, means for directly and mechanically translating Morse code signals comprising two signal 110 operated devices adapted to operate differently according to the value of each Morse impulse, a translating device adapted to move in two directions, means actuated by one of said signal operated devices adapted 115 positively to impart movement in one direction to the said translating device, means on said translating device, co-operating with the other signal operating device, selectively to control the movement of the translating 120 device in the other direction, said translating device integrating the individual movements until the signal is complete and thereby attaining a particular position determined by the signal and differing for 125 each of the individual signals to be received and means for returning the translating device to its initial position for the next signal.

7. In electric signalling apparatus, means 130

for directly and mechanically translating Morse code signals comprising two signal operated devices adapted to operate differently according to the value of each Morse impulse, a translating device adapted to move in two directions, means actuated by one of said signal operated devices adapted positively to impart movement in one direction to the said translating device, means 10 on said translating device co-operating with the other signal operating device, selectively to control the movement of the translating device in the other direction, said translating device integrating the individual 15 movements until the signal is complete and thereby attaining a particular position determined by the signal and differing for each of the individual signals to be received, a reproducing device operated by and corresponding to the translating device adapted 20 to bring a distinguishing mark corresponding to the signal into a certain position on the completion of each signal, means for printing the selected mark when the latter

is in position and means for returning the 25 translating and reproducing devices to their initial position for the next signal.

8. In electric signalling apparatus, means for directly and mechanically translating Morse code signals comprising two signal 30 operated devices adapted to operate differently according to the value of each Morse impulse, a translating device adapted to move in two different directions, an escape- 35 ment actuated by one signal operated device, positively to impart movement in one direction to the said translating device, means co- 40 operating with the other signal operated device adapted selectively to determine movement of the translating device in the other direction thereby moving the translating device into a position determined by the signal and differing for each individual signal, and means for returning the translating device to its initial position for the 45 next signal.

In testimony whereof I affix my signature.

THOMAS JAMES BERRYMAN.
